UNITED STATES PATENT OFFICE.

JOHN B. SALTERINI, OF NEW YORK, N. Y.

DESIGN FOR A BRIDGE LAMP.

Application filed February 4, 1928. Serial No. 25,201. Term of patent 3½ years.

To all whom it may concern:

Be it known that I, JOHN B. SALTERINI, a citizen of the United States, residing at New York, county of New York, and State of New York, have invented a new, original, and ornamental Design for Bridge Lamps, of which the following is a specification, reference being had to the accompanying drawing, forming part thereof.

I claim:

The ornamental design for a bridge lamp, as shown.

JOHN B. SALTERINI.
